UNITED STATES PATENT OFFICE.

JAN ZALIEWSKI, OF PITTSBURGH, PENNSYLVANIA.

RAILWAY-TIE CONSTRUCTION.

1,283,611.

Specification of Letters Patent.

Patented Nov. 5, 1918.

Application filed July 24, 1918. Serial No. 246,598.

To all whom it may concern:

Be it known that I, JAN ZALIEWSKI, a citizen of Russia, residing at S. S. Pittsburgh, in the county of Allegheny and State of Pennsylvania, have invented certain new and useful Improvements in Railway-Tie Construction, of which the following is a specification.

The primary object of the invention is 10 the provision of a railway tie provided with rail-attaching means adapted to be readily secured temporarily upon the tie without the employment of any locking devices, the invention, however, contemplating the use 15 of locking means when in actual use.

A further object of the invention is to provide a railway tie and rail fastener that is easy and inexpensive to manufacture, the same being capable of use in temporary 20 track construction as well as in the construction of a permanent track.

With these general objects in view, the device will now be specifically described and thereafter claimed in connection with the 25 accompanying drawing and in which like reference characters designate corresponding parts throughout the several views.

In the drawing,

Figure 1 is a side elevation of my device 30 assembled with railway ties mounted thereon and shown in vertical transverse section;

Fig. 2 is a top plan view thereof;

Fig. 3 is a bottom plan view of one end 35 of the tie with the attaching means in position;

Fig. 4 is a vertical transverse sectional view taken upon line IV—IV of Fig. 1;

Fig. 5 is a perspective view of the bottom of an end portion of the tie with the attaching means removed; and

Fig. 6 is an inverted perspective view of a portion of one of the attaching plates employed with my form of tie.

My invention provides an elongated rectangular tie 10 having a longitudinal recess 11 in the bottom thereof and a longitudinal upwardly projecting seat portion 12 upon the top of the tie adapted for supporting railway rails 13 transversely positioned 50 upon said seat accurately spaced apart the proper gage of the road.

A pair of attaching blocks 14 is provided for each end of the tie adapted for flatly positioning upon the seat 12 at opposite 55 sides of the rails 13 and having finger por-

tions 15 overlying the adjacent base flanges 16 of said rails.

Three depending posts 17 are carried by each block 14 adapted to project downwardly through transversely extending slots 60 18 in the tie 10. U-shaped shoulders 19 are provided in the slots 18 adjacent corresponding sides thereof adapted for permitting oppositely projecting ribs 20 at the free ends of the posts 17 to position themselves 65 beneath the shoulders 19 when the posts 17 are moved laterally of the tie to the other end of said slots 18. This assembling of the blocks 14 upon the tie 10 is a simple and easy operation, it being seen that the posts 70 17 with their ribs 20 are readily projected downwardly through the main portion of the slots 18 while upon shifting the blocks 14 laterally of the seat 12, the ribs 20 will engage beneath the shoulders 19, thereby retaining the blocks in position upon the tie 75 10, securing the rails 13 to the seat 12.

The tie and rail-securing means may be employed as a temporary track when quickly assembled in this manner but when the track 80 is to be permanent, bolts 21 are upwardly inserted through the slots 18 at the sides of the posts 17 and extend through perforations 22 in the blocks 14 positioned adjacent the said posts.

Heads 23 are provided for the bolts 21 seating within the recess 11 at the bottom of the tie 10 and overlying the slots 18, as illustrated in Figs. 3 and 4 of the drawing; while nuts 24 are threaded upon the upper 90 ends of said bolts bearing against the upper faces of the blocks 14. When the blocks 14 are secured against lateral movement by the bolts 21, the posts 17 are firmly locked within the slots 18 and the rails are retained in 95 permanent track formation until the nuts 24 are released and the bolts 21 are removed permitting the blocks 14 to be readily disengaged from the rails 13 and detached from the tie 10.

What I claim as new is:—

1. A tie and rail fastener comprising a tie adapted for transversely mounting a rail thereon and having a plurality of transverse slots positioned at opposite sides of the rail-receiving portion and with shoulders at corresponding ends of said slots, attaching blocks upon the tie having projecting fingers adapted for overlying the base flanges of a rail when in position upon said portion, de- 110

- pending posts upon said blocks having projecting ribs at their free ends, the said posts and ribs being adapted for positioning through the main portion of said slots for engaging the ribs thereof beneath the said shoulders upon laterally sliding the said blocks, the bottom of said tie having a longitudinal recess surrounding the open lower ends of said slots, bolts upwardly projecting through said slots, blocks adjacent the said posts and provided with enlarged heads within said recess overlying the sides of said slots, and securing nuts upon the upper ends of said bolts engaging said blocks.
- 15 2. A device of the class described comprising an elongated tie having a longitudinal recess in the bottom thereof and an upwardly projecting rail seat upon the top of the tie, the said tie being provided with
- 20 pairs of sets of transverse slots vertically extending therethrough adjacent the opposite ends of said seat adapted for the positioning of rails between the slots of each set transversely of the seat, a rail-engaging
- 25 block for each set of slots, U-shaped shoulders provided in said slots adjacent corresponding ends thereof, dependent posts upon said blocks adapted for vertical positioning through said slots and having projecting ribs upon their free ends adapted for underlying the said shoulders when the device is
- 30 assembled with the blocks in their opera-
- tive positions upon the rail-seating portion of the tie.
3. A device of the class described comprising an elongated tie having a longitudinal recess in the bottom thereof and an upwardly projecting rail seat upon the top of the tie, the said tie being provided with pairs of sets of transverse slots vertically extending therethrough adjacent the opposite ends of said seat adapted for the positioning of rails between the slots of each set transversely of the seat, a rail-engaging block for each set of slots, U-shaped shoulders provided in said slots adjacent corresponding ends thereof, dependent posts upon said blocks adapted for vertical positioning through said slots and having projecting ribs upon their free ends adapted for underlying the said shoulders when the device is assembled with the blocks in their operative positions upon the rail-seating portion of the tie, the said blocks having perforations adjacent the said posts, bolts upwardly extending through the said perforations and slots at the opposite ends of the slots from said shoulders with heads overlying the lower ends of the slots and positioned within said recess, and securing nuts upon the upper ends of said bolts engaging the upper faces of the blocks.

In testimony whereof I affix my signature.
JAN ZALIEWSKI.
